UNITED STATES PATENT OFFICE.

GEORGE F. WINGATE, OF RIVERSIDE, ILLINOIS.

WAGON-TONGUE SUPPORT.

SPECIFICATION forming part of Letters Patent No. 234,446, dated November 16, 1880.

Application filed January 30, 1880.

To all whom it may concern:

Be it known that I, GEORGE F. WINGATE, residing at Riverside, in the county of Cook and State of Illinois, and a citizen of the United States, have invented a new and useful Improvement in Wagon-Tongue Supports, of which the following is a full description, reference being had to the accompanying drawings, in which—

10 Figure 1 is a top or plan view, Fig. 2, a longitudinal section, Fig. 3 an under-side view, Figs. 4, 5, and 6 details, of the support for the tongue.

Only so much of a complete wagon as is necessary to show the application of the device is shown in the drawings.

15 The forward end of the tongue or pole of a wagon or vehicle should be supported in an elevated position sufficiently high to keep the weight thereof off from the necks of the horses, and in such manner as to allow such forward end to be raised when desired and at the same time prevent it from falling, so as to throw the weight thereof downward.

20 To accomplish these results and to adjust the elevation so as to accommodate it to the height of the horses are the objects of this invention; and its nature consists in providing an adjusting-piece having an inclined or 25 wedge shape, and located on a bar or support, the rear end of which will be in contact with the fore axle of the wagon or vehicle, and the front end with the tongue at a sufficient distance forward to furnish the required support, 30 the bar passing through and being supported by a loop or hanger depending from the coupling bolt or rod of the tongue or other suitable point, and the wedge or incline engaging with such depending loop for adjusting the 35 height of the forward end of the tongue.

In the drawings, A represents a piece of wood or other suitable material of a sufficient length to allow its rear end to come beneath the fore axle, and its front end beneath the 40 tongue at the required distance forward to keep its front end in an elevated position, the length varying with different make of vehicles; but such length and point of contact on the tongue must be one that will bear the 45 weight of the tongue or pole.

a is a piece of wood or other material hav-

ing an inclined or wedge shape, and attached to the under side of the bar or support A. As shown, this wedge or incline is attached by means of a strap or loop, b, in such manner 55 that it can be moved forward or back, as required; but it may be attached by any other suitable means, and, if desired, it may be attached so as to remain stationary.

B is a piece of iron or other material, bent 60 so as to have a stirrup shape, the sides of which have hooks or eyes for attaching it in place, so that it can receive and support the bar A. As shown, this loop or hanger B is held in position by hooking the side pieces 65 over the coupling rod or bolt c of the tongue; but it may be attached in any other suitable manner.

C is an ordinary tongue having hounds C'. D is the fore axle made in any of the usual 70 forms.

E are the fore hounds, between the forward ends of which is secured the tongue-hounds in the usual manner by means of the coupling rod or bolt c.

75 d is the ordinary hammer or bolt for attaching the double-tree.

e is the slot in the rear end of A for the passage of the king-bolt. This slot is not necessary, except in cases where the end of the 80 king-bolt projects below the axle. As shown, the front end of A is attached to the tongue by the hammer or bolt d; but any suitable attachment that will prevent slipping may be used.

85 In use the hanger or loop B is hooked or otherwise attached to the rod or bolt c, so as to depend therefrom. The bar A is then passed through it until its rear end is in contact with the under side of the axle, bringing 90 its front end beneath the tongue, and the wedge or incline a resting on the cross-piece of the stirrup or hanger B, by which means the tongue will be held up or in an elevated position, and cannot drop, but is free to be raised when desired. If the tongue at its front end is to be 95 raised or lowered it can be easily done by moving the wedge or incline forward or back, so as to bring a thinner or thicker portion in contact with the cross-piece of the hanger or stirrup B.

100 When the wedge or incline is firmly at-

tached to the bar A the bar itself can be moved forward or back for adjusting purposes, in which case the attachment of the front end to the pole would have to be an adjustable one.

5 The bolt or coupling-rod *c* furnishes an efficient means from which to depend the stirrup; but it could be attached to the fore hounds by other devices, so as to bring it properly in position to receive and support the bar A.

10 What I claim as new, and desire to secure by Letters Patent, is—
In a wagon-tongue support consisting of a

bar, A, the rear end of which is in contact with the fore axle, and the front end with the tongue, and a depending loop or hanger, B, to receive and support the bar, a wedge or incline, *a*, located on the bar A, and arranged to engage the loop or hanger B, for adjusting the forward end of the tongue, substantially as specified.

GEORGE F. WINGATE.
